ELECTROLYTIC REDUCTION OF SUGARS IN
ACID SOLUTIONSRalph A. Hales, Tamaqua, Pa., assignor to Atlas
Powder Company, Wilmington, Del., a corpora-
tion of DelawareNo Drawing. Application January 7, 1939,
Serial No. 249,705

14 Claims. (Cl. 204—77)

This invention relates to the electrolytic reduction of sugars to polyhydric alcohols and more particularly to such reduction while maintaining the bulk of the sugar in an acid solution.

It has heretofore been proposed to electrolytically reduce glucose in an acid solution (see German patent to Gunn, No. 140, 318) but subsequent investigations have not been able to duplicate this work. See the published papers of Loeb, Z. Elektrochem, 16, 1 (1910), of Findlay and Williams, Trans. Faraday Soc., 17, 453 (1921-1922) and of Hibbert and Read, J. A. C. S., 46, 983 (1924). My own attempts to duplicate the work of Gunn have likewise been wholly unsuccessful.

The principal object of the present invention is to devise a highly successful process for the electrolytic reduction of sugars while maintaining the bulk of the sugar throughout the reduction in an acid solution.

Another object of the present invention is to devise a process for the electrolytic reduction of sugars to polyhydric alcohols which yields a product of greatly improved color and color stability.

Other objects will more fully hereinafter appear.

The process of reduction and apparatus employed are similar to those disclosed in United States Letters Patent to Creighton, Number 1,990,582. In accordance with that patent, the electrolytic reduction is carried out in a cell having a catholyte comprising an aqueous solution of one or more reducible saccharides and sodium sulfate or other suitable alkali metal compound. The catholyte is in contact with a cathode which serves to maintain the catholyte in an alkaline condition, and which is separated from the anolyte, comprising an aqueous solution of sulfuric acid, by a porous diaphragm. The porous diaphragm permits hydrogen ions to pass from the anode compartment into the cathode compartment and permits the passage of sulphate ions from the cathode compartment to the anode compartment but is sufficiently impermeable to prevent the diffusion of the catholyte into the anode compartment. The anode in contact with the anolyte may consist of chemical lead or lead coated with lead dioxide. When electric current is passed through the cell, sulfate ions are discharged at the anode, reacting with the water forming oxygen and sulfuric acid adjacent the anode. In the catholytic section of the cell, sodium ions migrate to the cathode, are discharged and unite with the water, forming nascent hydrogen and sodium hydroxide. The nascent hy-

drogen thus formed in the catholyte reduced the saccharide in the catholyte to a polyhydric alcohol.

Now I have found that sugar may be successfully reduced to a polyhydric alcohol while maintaining the main body of catholyte in acid condition, provided the acid catholyte contains an alkali metal sulfate. During electrolysis, such a catholyte is made alkaline in the region immediately surrounding the cathode so that reduction is made possible even though the main body of catholyte is acidic. There is a continuous formation of a thin film or layer of alkaline catholyte around the cathode. The alkaline conditions thus brought about at the cathode cause transformation of the saccharide to a form in which it is reducible to a polyhydric alcohol by the action of the nascent hydrogen liberated at the cathode.

In the process of the present invention, the catholyte is rendered acid prior to the beginning of reduction and is kept acid throughout the reduction by the addition of necessary amounts of acid from time to time. The electrolytic action causes the formation of alkali hydroxide at the cathode from which it emanates into the catholyte, thereby tending to continually render the main body of the catholyte alkaline, and this must be prevented by neutralizing periodically in order to maintain the main body of the catholyte on the acid side.

During reduction on the acid side in accordance with the process of this invention, the main body of the catholyte is at a pH of less than 7.0, and accordingly the saccharide in the main body of the catholyte is protected against the deleterious effect of a prolonged action of alkali hydroxide thereupon. As a result, the polyhydric alcohol product of this invention is of better color, better thermal-stability, and is lower in objectionable impurities such as organic acids and alkali salts thereof. In addition to the production of a superior product, by reason of the elimination of the degradative effect of alkali upon the sugar, the reduction of saccharides to polyhydric alcohol in accordance with the present invention is carried out at an economical speed with high current efficiency and high yield.

The acidity of the main body of the catholyte may be varied from a pH of just under 7.0 down to a pH of 1.5 or even lower. In practice, due to the uneconomic reduction speeds obtained at a pH below 1.5, it will be found preferable to operate at a pH not lower than 1.5, although where lower reduction speeds are unobjectionable, a pH

of below 1.5 may be employed. Generally, it is recommended that the reduction be conducted with the main body of the catholyte at a pH of not lower than 2.3 because of the much greater reduction rate obtained.

The concentration of sugar in the catholyte will usually be in the neighborhood of 325 grams per liter although, obviously, smaller or larger amounts may be employed. Likewise, while the concentration of sodium sulfate or other alkali sulfate in the catholyte will usually be around 50 to 90 grams per liter, smaller or greater concentrations of this ingredient may be used. Thus, variations in sodium sulfate concentration of from 5 to 125 grams per liter give about the same rate of reduction under otherwise identical conditions, and provided the pH is the same. However, for a given pH the acidity in grams H_2SO_4 per liter increases as the alkali sulfate content is increased because of the buffer action of the alkali sulfate.

Any alkali sulfate may be used in the catholyte. Sodium sulfate is preferred on the ground of cheapness, but potassium sulfate gives somewhat higher rates of reduction and may be used. Ammonium sulfate gives a fair rate of reduction. Lithium sulfate gives a lower rate of reduction than any of the other alkali sulfates mentioned and therefore while it may be used, it is not preferred.

The temperature of the catholyte during reduction is preferably maintained at around 69° F. although considerably higher temperatures may be employed. However, with all other conditions the same, an increase in the temperature with the process of the present invention does not speed up the reduction, whereas when reducing with the main body of the catholyte alkaline, the effect of an increase in temperature is to speed up the reduction. With the main body of the catholyte acidic, the failure of an increase in temperature to speed up the reduction may be attributed to a lowering of the viscosity of the catholyte at higher temperatures, causing a faster diffusion of the acid catholyte through the alkali film formed on the cathode.

The mechanism of reduction in the process of the present invention is not clearly understood, but it has been found that under the conditions employed the cathodes maintain a surrounding layer of catholyte containing alkali hydroxide even though the main body of the catholyte is acid. Thus, an L-shaped tube with a capillary opening at the tip was slowly lowered into the catholyte at various times during the reduction, the tip being pointed towards and touching the cathode, and samples of the catholyte next to the cathode were taken. These samples were all slightly alkaline with alkali hydroxide.

By proceeding in accordance with the present invention, the main body of the unreduced sugar is kept under stable conditions and yet as the sugar comes into contact with the cathode, the thin film of alkali thereupon causes enolization of the sugar to the form in which it is readily reduced to the corresponding polyhydric alcohol by the nascent hydrogen liberated at the cathode. It was most surprising to find that reduction could be carried out in this manner with the main body of the catholyte in acid condition, thereby preserving the bulk of the unreduced sugar against prolonged attack by alkali. In the absence of an alkali sulfate, I have found that it is impossible to carry out reduction with the main body of the catholyte in acid condition, and this

may perhaps be explained by the statement that in the absence of an alkali salt an alkali film cannot form on the surface of the cathode.

In carrying out the process of the present invention, the effect of the use of higher current densities is to permit the use of a catholyte of lower pH. An increase in current density appears to cause an increase in the rate of formation of the alkali film on the cathode, which increased rate seems to counteract the tendency of catholytes of high acidity to slow up the reduction. The effect of variations in current density upon the rate of reduction is, therefore, much more pronounced when employing the process of the present invention than when carrying out a reduction with the main body of the catholyte on the alkaline side.

The cathodes employed in carrying out the reduction may be of amalgamated solid metal such as amalgamated zinc or lead, or of suitable unamalgamated metal such as zinc, or of carbon or graphite.

While the invention is particularly applicable to the reduction of monosaccharides, one of its advantages is that it may be applied to disaccharides such as sucrose, which may be inverted by the acid in the catholyte and substantially simultaneously the monosaccharide inversion products may be reduced to the corresponding polyhydric alcohols. An example of such procedure is Example 17 below.

The invention is also applicable to the direct reduction of reducible oligo-saccharides such as reducible disaccharides, such as lactose, to the corresponding polyhydric alcohol. An example of this is Example 18 below wherein lactose is reduced directly to lactositol.

The process of the present invention has a marked advantage over reductions wherein the main body of the catholyte is alkaline in that the present process yields a product of improved properties. Thus, the thermal stability of the products of the present process is outstanding. Sorbitol syrup made in accordance with the present invention increases in color only very slightly upon heating, say from 6 to 22½ hours at 90° C., and is in this respect greatly superior to sorbitol syrups produced with the main body of catholyte in alkaline condition. The improved thermal stability is due to the very small proportions of color-forming bodies present in the product. Formation of these color-forming bodies is prevented by the elimination of the destructive action of alkali upon the sugar and upon the products of reduction in the main body of the catholyte.

Below are a number of non-limiting specific examples of reductions wherein the main body of the catholyte was acid. In each example the catholyte was processed in accordance with the process disclosed in U. S. Patent 2,116,665 to recover the polyhydric alcohol therefrom.

Example 1

Glucose was electrolytically reduced to a sorbital syrup at amalgamated lead cathodes at a temperature of 68° F. The catholyte was an aqueous solution of glucose, sodium sulfate and sulfuric acid in the proportions of 325 grams of magnesium-free glucose per liter, 75 grams of magnesium-free sodium sulfate per liter and 0.1 gram of magnesium-free H_2SO_4 per liter. The anolyte was an aqueous solution of 300 grams C. P. sulfuric acid per liter. The volume of catholyte used was 3.36 liters, and the cathode sur-

face was 8.15 square decimeters. The current density at the cathode was 1.10 amperes per square decimeter during the first part of reduction and after approximately 65% of the sugar had been reduced, which was after 50 hours, it was reduced to 0.55. The main body of the catholyte was maintained at an acidity of approximately 0.1 gram per liter and a pH of approximately 3.6 throughout the reduction by the addition to the catholyte of the required amounts of sulfuric acid at frequent periodic intervals during the reduction. After 117 hours, when the glucose was 87.8% reduced, the cell was shut down. The yield of polyhydric alcohol was 97.8% of the theoretical. The product was a sorbitol syrup having a pyridine number of 83.0.

Example 2

This reduction was carried out following identically the conditions of Example 1 except that the catholyte was maintained at an acidity of about 1.0 gram H_2SO_4 per liter and at a pH of approximately 2.2. The current density was reduced from 1.1 to 0.55 amps. per sq. dm. after 67 hours, when approximately 65% of the glucose had been reduced. 177.5 hours were required to reduce 87.0% of the glucose, whereupon the cell was shut down. The yield of polyhydric alcohol was 100% of the theoretical and the product was sorbitol syrup with a pyridine number of 80.5.

For purposes of comparison, it was attempted to reduce glucose under identically the same conditions as above but using no alkali sulfate in the catholyte and using an anolyte consisting of an aqueous solution of only 250 grams H_2SO_4 per liter. A current density of 1.1 amps. per sq. dm. was used throughout the run except in the latter part where this current density could not be maintained on account of the high voltage at low acidity. Sulfuric acid was added to the catholyte as required to maintain the acidity at a pH of approximately 2.2. The current was passed for 72.3 hours when tests showed that no sugar had been reduced. Thereupon the run was ended. No product was obtained.

Example 3

The reduction was carried out as in Example 1, except that the temperature was 72° F. and the acidity of the main body of the catholyte was maintained at between 0.1 and 0.5 gram H_2SO_4 per liter, being 0.4 gram per liter at the start. Appropriate periodic additions of H_2SO_4 were made to keep the acidity within the above range. The sugar was approximately 65% reduced after 32 hours of operation, at which time the current density was reduced from 1.1 to 0.55 amps. per sq. dm. After 116 hours 98.6% of the sugar had been reduced and the run was ended. The yield of polyhydric alcohol was 90.2% of the theoretical. The product was a sorbitol syrup having a pyridine number of 73.5.

Example 4

This was like Example 3 except that the temperature was 76° F. and the acidity of the catholyte was between 0.1 and 0.7 gram H_2SO_4 per liter. The glucose was approximately 65% reduced after 42 hours, at which time the current density was reduced from 1.1 to 0.55 amps. per sq. dm. After 142 hours, 99.0% of the glucose had been reduced and the run was ended. The yield was 94.0% of the theoretical and the product was a sorbitol syrup having a pyridine number of 77.5.

5 10 15

Example 5

Glucose was reduced under the same conditions as in Example 1 except that the temperature was 72° F. The acidity was maintained throughout at between 0.1 and 1.5 gms. H_2SO_4 per liter, the initial acidity being 1.5 gms. H_2SO_4 per liter. As in Example 1 the current density was reduced from 1.1 to 0.55 amps. per sq. dm., when approximately 65% of the sugar was reduced, which was at 42 hours. In 205 hours the glucose was 98.5% reduced and the run was ended. The yield was 93.0% of the theoretical. The product was a water-white sorbitol syrup having a pyridine number of 65.0.

30

Example 6

Glucose was reduced under the same conditions as in Example 5, except that the current density was maintained throughout at 1.1 amps. per sq. dm. instead of being lowered to 0.55 when 65% of the sugar had been reduced. The rate of reduction during the latter part of the run was increased by employing the higher current density during that portion of the run. The glucose was 99.0% reduced after 134 hours, at which time the run was ended. The yield was 96.1% of the theoretical and the product was a water-white sorbitol syrup having a pyridine number of 74.5.

35

Glucose was electrolytically reduced at amalgamated zinc cathodes under the following conditions: The temperature was maintained at 69° F. The current density was 1.0 amps. per sq. dm. throughout the run. The ratio of cathode area in sq. dm. to volume of catholyte in liters was 2.0. The acidity was maintained between 0.5 and 1.5 gms. H_2SO_4 per liter and a pH of around 2.7. The catholyte solution originally contained 325 gms. magnesium-free glucose per liter, and 75 gms. magnesium-free sodium sulfate. In 104 hours the sugar was 99.0% reduced. The yield of polyhydric alcohol was 90.8% of the theoretical. The product was a water-white sorbitol syrup having a pyridine number of 66.5. The organic acid sodium salt content of the product was extremely low—0.01% (reported as sodium sulfate).

40

Glucose was reduced under the same conditions as in Example 7 except that the temperature was maintained at 80° F. The glucose was 99.2% reduced in 101.5 hours. The yield was 92% of the theoretical. The product was a water-white sorbitol syrup having a pyridine number of 62 and an organic acid sodium salt content of 0.04% (reported as sodium sulfate).

45

Glucose was reduced under the same conditions as in Example 7 except that the temperature was maintained at 120° F. The glucose was 98.4% reduced in 99 hours. The yield was 86.7% of the theoretical. The product was a very light lemon colored sorbitol syrup having a pyridine number of 42 and an organic acid sodium salt content of 0.10% (reported as sodium sulfate).

50

Glucose was reduced exactly as in Example 7 except that the acidity was greater, being maintained at between 1.5 and 2.5 gms. H_2SO_4 per liter at a pH of around 2.3 and that the catholyte contained 69 gms. of Na_2SO_4 per liter. The sugar was 94.4% reduced after 231 hours. The

55

60

65

70

75

Example 8

Glucose was reduced under the same conditions as in Example 7 except that the temperature was maintained at 80° F. The glucose was 99.2% reduced in 101.5 hours. The yield was 92% of the theoretical. The product was a water-white sorbitol syrup having a pyridine number of 62 and an organic acid sodium salt content of 0.04% (reported as sodium sulfate).

Example 9

Glucose was reduced under the same conditions as in Example 7 except that the temperature was maintained at 120° F. The glucose was 98.4% reduced in 99 hours. The yield was 86.7% of the theoretical. The product was a very light lemon colored sorbitol syrup having a pyridine number of 42 and an organic acid sodium salt content of 0.10% (reported as sodium sulfate).

Example 10

yield was 87.3% of the theoretical. The product was a water-white sorbitol syrup having a pyridine number of 70.0 and no measurable organic acid sodium salt content.

Example 11

Glucose was reduced under the same conditions as in Example 10 except that 75 grams of magnesium-free ammonium sulfate per liter were used as the alkali sulfate. The sugar was 94.9% reduced in 339 hours and the yield of polyhydric alcohol was 88.7% of the theoretical. The product was a sorbitol syrup having a pyridine number of 77.5.

Example 12

Glucose was reduced under the same conditions as in Example 10 except that 69 gms. of magnesium-free potassium sulfate per liter were used as the alkali sulfate and the acidity of the main body of the catholyte was maintained at between 1 and 2 gms. H₂SO₄ per liter and the pH at approximately 2.3. After 121 hours the glucose was 99.1% reduced. The yield of polyhydric alcohol was 91.6% of theoretical. It was a water-white sorbitol syrup with a pyridine number of 71.5.

Example 13

Glucose was reduced exactly as in Example 12 except that 69 grams of magnesium-free lithium sulfate per liter were employed as the alkali sulfate, the pH was maintained at around 2.2 and the acidity at between 1 and 2 gms. H₂SO₄ per liter. After 114 hours only 25.8% of the glucose had been reduced and the run was thereupon ended. The yield of polyhydric alcohol was 92.1% of the theoretical. The product was a sorbitol syrup.

Example 14

Glucose was electrolytically reduced at amalgamated zinc cathodes in a catholyte containing 325 gms. of magnesium-free glucose per liter, 75 gms. of magnesium-free sodium sulfate per liter, the main body of the catholyte being maintained at an acidity of from 2.5 to 3.5 gms. H₂SO₄ per liter and at a pH of approximately 2.1. The current density was maintained at 1.0 amps. per sq. dm. of cathode area. The ratio of cathode area in sq. dm. the catholyte volume in liters was 2.0. After 137 hours 48.9% of the sugar had been reduced and the run was thereupon discontinued. The yield of polyhydric alcohol (sorbitol) was 87.0% of theoretical.

Example 15

Glucose was reduced exactly as in Example 14 except that 75 grams of K₂SO₄ per liter were used as the alkali sulfate. After 193 hours 87.0% of the glucose had been reduced. Subsequent reduction was very slow for after 239 hours only 88.0% of the glucose had been reduced. The run was then ended. The yield of polyhydric alcohol was 85.0% of the theoretical. The product was a water-white sorbitol syrup having a pyridine number of 75.0 and containing organic acid sodium salt content of 0.07% (reported as sodium sulfate).

Example 16

Glucose was reduced at amalgamated zinc cathode, the catholyte initially containing 325 gms. glucose per liter and 75 gms. Na₂SO₄ per liter. The current density was 4.0 amps. per sq. dm. of cathode area. The temperature was 75

maintained at 74° F. The ratio of cathode area to catholyte volume was 2.0 sq. dm. per liter. The pH was maintained throughout the reduction at approximately 1.9 and the acidity at 3.5 to 4.5 gms. H₂SO₄ per liter of catholyte. After 42 hours, 99% of the glucose was reduced. The current efficiency was 27.2%. The product was a water-white sorbitol syrup having a pyridine number of 66.5, and an organic acid sodium salt content of 0.02% calculated as sodium sulfate. The yield was 95.4% of the theoretical.

Example 17

This example shows substantially simultaneous inversion of a non-reducible disaccharide and reduction of the inversion products, yielding two polyhydric alcohols.

An aqueous solution of sucrose containing 325 gms. sucrose per liter was acidified with H₂SO₄ to a pH of 2.3. It was then placed in the cathode compartment of an electrolytic reduction cell having amalgamated zinc cathodes, and reduction was begun. The current density was 1.0 amp. per sq. dm. and the temperature was maintained at 81° F. The ratio of cathode area to catholyte volume was 1.21 sq. dm. per liter. A relatively large volume of solution (i. e. a low sq. dm./L ratio) was used so that the rate of inversion of the sucrose would be appreciably higher than the rate of reduction of the invert sugar so produced, and so that reduction might not be delayed by reason of an insufficient concentration of invert sugar in the catholyte, sucrose being not directly reducible because of its molecular configuration. The concentration of H₂SO₄ was maintained at between 1-2 gms. H₂SO₄ per liter. The initial concentration of sodium sulfate in the catholyte was 75 gms. per liter. After 425 hours 90% of the sucrose had been inverted and reduced. The current efficiency was 16.1%. The yield was 90.3% of the theoretical. The product consisted of mannitol in an amount equal to 18.0% of the total polyhydric alcohol yield and a water-white sorbitol syrup having a pyridine number of 52.0 and an organic acid sodium salt content of 0.03% calculated as sodium sulfate.

Example 18

This example shows reduction of a reducible disaccharide directly to the corresponding polyhydric alcohol, no appreciable inversion of the disaccharide taking place.

Lactose in the form of an aqueous solution containing 325 grams of lactose monohydrate was reduced in an electrolytic cell at amalgamated zinc cathodes. The current density was 1.0 amp. per sq. dm. The temperature was maintained at 80° F. The ratio of cathode area to catholyte volume was 1.21 sq. dm. per liter. The initial pH was 2.3. The acidity was maintained at 1.5-2.5 gms. H₂SO₄ per liter. The initial sodium sulfate concentration was 75 gms. per liter. 90% of the sugar had been reduced in 660 hours. The current efficiency was 4.9%. The product was a water-white syrup consisting chiefly of lactositol. No polyhydric alcohol of limited solubility in water, such as mannitol or dulcitol, was formed in appreciable amounts, and the pyridine number of the syrup was 0.0.

From the foregoing description it will be seen that I have devised a successful process for the electrolytic reduction of reducible saccharides to polyhydric alcohols while maintaining the main body of the catholyte on the acid side, which

results in numerous advantages, among which is the greatly reduced opportunity for alkali degradation of the sugar with the consequent production of objectionable color, of high organic acid content, of poor heat-stability of the product, etc.

In this specification and in the claims appended hereto, by the expression "main body of the catholyte" I mean the entire catholyte with the exception of a film of catholyte surrounding the cathode, which film is maintained in an alkaline condition at the cathode by electrolysis with a catholyte containing an alkali metal sulfate, as herein explained. By "reducible saccharides" I mean the mono-saccharides, and the oligosaccharides which will reduce Fehling's solution, these being the saccharides which are directly reducible to polyhydric alcohols.

Having described my invention, what I claim is:

1. The process for producing a sorbitol-containing product which comprises electrolytically reducing glucose in an aqueous solution comprising substantial amounts of sulfuric acid and sodium sulfate as the catholyte in contact with the cathode in the catholyte compartment of an electrolytic diaphragm cell, and maintaining said catholyte at a pH substantially less than 7.0 and not less than about 1.5 throughout the reduction.

2. The process for producing polyhydric alcohol which comprises electrolytically reducing a reducible sugar in an aqueous solution comprising substantial amounts of strong acid and an alkali metal sulfate as the catholyte in contact with the cathode in the catholyte compartment of an electrolytic diaphragm cell, and maintaining the catholyte at a pH of substantially less than 7.0 and not lower than about 2.3 throughout the reduction.

3. The process for producing polyhydric alcohol which comprises electrolytically reducing a reducible sugar in an aqueous solution comprising a substantial amount of acid and an alkali metal sulfate as the catholyte in contact with the cathode in the catholyte compartment of an electrolytic diaphragm cell, said acid being present in amount to give the catholyte a pH substantially less than 7.0 and not lower than about 1.5, and continuously maintaining the pH of the catholyte within said values throughout the reduction.

4. The process for producing a hexitol-containing product which comprises electrolytically reducing a monosaccharide in an aqueous solution comprising substantial amounts of an alkali metal sulfate and of sulphuric acid as the catholyte in contact with the cathode in the catholyte compartment of an electrolytic diaphragm cell, and maintaining the catholyte at a pH substantially less than 7.0 and not lower than about 1.5 throughout the reduction.

5. The process for producing polyhydric alcohol which comprises electrolytically reducing a reducible sugar in an aqueous solution comprising substantial amounts of an alkali metal sulfate and sulfuric acid as the catholyte in contact with the cathode in the catholyte compartment of an electrolytic diaphragm cell, and maintaining the catholyte at a pH substantially less than 7.0 and not less than about 2.3 throughout the reduction.

6. The process for producing a sorbitol-containing product which comprises electrolytically reducing glucose in an aqueous solution comprising substantial amounts of an alkali metal

sulfate and sulfuric acid as the catholyte in contact with the cathode in the catholyte compartment of an electrolytic diaphragm cell, said acid being present in amount sufficient to give the catholyte a pH of substantially less than 7.0 and not lower than about 1.5, and maintaining the catholyte at a pH substantially below 7.0 and not less than about 1.5 throughout the reduction.

7. The process for producing polyhydric alcohol which comprises electrolytically reducing a reducible sugar in an aqueous solution comprising an alkali metal sulfate and sulphuric acid as the catholyte in contact with the cathode in the catholyte compartment of an electrolytic diaphragm cell, and maintaining the pH of the catholyte substantially below 7.0 and not less than about 1.5 throughout the reduction.

8. The process for producing polyhydric alcohol which comprises electrolytically reducing a reducible sugar in an aqueous solution with sulfuric acid as the catholyte in contact with the cathode in the catholyte compartment of an electrolytic diaphragm cell, said catholyte further comprising from 5 to 125 grams sodium sulfate per liter, and maintaining the pH of the catholyte substantially less than 7.0 and not less than about 1.5 during the reduction.

9. The process for producing polyhydric alcohol which comprises substantially simultaneously inverting a disaccharide in an aqueous solution with a strong acid and electrolytically reducing the inversion products as the catholyte in contact with the cathode in the catholyte compartment of an electrolytic diaphragm cell, said catholyte comprising a substantial amount of an alkali metal sulfate, and maintaining said catholyte at a pH substantially less than 7.0 and not less than about 1.5 throughout the reduction.

10. The process for producing polyhydric alcohol which comprises substantially simultaneously inverting sucrose in an aqueous solution with a substantial amount of a strong acid and electrolytically reducing the inversion products as the catholyte in contact with the cathode in the catholyte compartment of an electrolytic diaphragm cell, said catholyte comprising a substantial amount of an alkali metal sulfate, and maintaining said catholyte at a pH substantially below 7.0 and not less than about 1.5 throughout the reduction.

11. The process for producing polyhydric alcohol which comprises substantially simultaneously inverting sucrose in a substantially acid aqueous sulfuric acid solution and electrolytically reducing the inversion products as the catholyte in contact with the cathode in the catholyte compartment of an electrolytic diaphragm cell, said catholyte comprising a substantial amount of an alkali metal sulfate, and maintaining said catholyte at a pH substantially less than 7.0 and not less than about 1.5 throughout the reduction.

12. The process for producing a polyhydric alcohol which comprises electrolytically reducing a reducible disaccharide in an aqueous solution comprising substantial amounts of strong acid and an alkali metal sulfate as the catholyte in contact with the cathode in the catholyte compartment of an electrolytic diaphragm cell, and maintaining said catholyte at a pH substantially less than 7.0 and not less than about 1.5 throughout the reduction.

13. The process for producing lactositol which comprises electrolytically reducing lactose in an aqueous solution comprising substantial amounts

of strong acid and an alkali metal sulfate as the catholyte in contact with the cathode in the catholyte compartment of an electrolytic dia-phragm cell, and maintaining said catholyte at a pH substantially below 7.0 and not less than about 1.5 throughout the reduction.

14. The process for producing lactositol which comprises electrolytically reducing lactose in an

5 aqueous solution comprising substantial amounts of sulfuric acid and an alkali metal sulfate as the catholyte in contact with the cathode in the catholyte compartment of an electrolytic dia-phragm cell, and maintaining said catholyte at a pH substantially below 7.0 and not less than about 1.5 throughout the reduction.

RALPH A. HALES.
